TIMING DEVICE

Lee A. Du Rocher, Goodhope, La.

Application June 12, 1934, Serial No. 730,294

1 Claim. (Cl. 161—1)

This invention relates to a timing device for games and is especially adapted for use by a time-keeper of a boxing match or prize fight or may be used for training persons to different periods of time and has for the primary object the provision of a device of the above stated character whereby playing or fighting periods, rest periods and warning periods preceding playing or fighting periods within the rest periods may be accurately given by the timekeeper through the aid of an electrically actuated time controlled mechanism.

Another object of this invention is the provision of signal means for indicating periods of time of one second each at any time or within the playing or fighting periods so that an accurate count may be made when a person is down or out in the fighting ring.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a front elevation illustrating a timing device constructed in accordance with my invention.

Figure 2 is an end elevation illustrating the same.

Figure 3 is a diagrammatical view illustrating the wiring diagram of the device.

Referring in detail to the drawing, the numeral 1 indicates a base on which is mounted an electrically actuated time clock 2, the dial of which is graduated for sixty seconds and over which is moved a second hand 3 and a minute hand 4. The electric motor 5 of the time clock 2 is electrically connected in an electric circuit composed of feed conductors 6 and 7. The conductor 7 has connected thereto a main control switch 8 for starting and stopping the clock 2. The motor 5 drives a signal control mechanism 9 mounted on the base and consists of a toothed wheel 10 rotatably supported and connected to the motor 5 by a sprocket chain and gearing so that the toothed wheel rotates in the direction of the arrow in Figure 1 and makes a complete revolution each minute during the operation of the clock 2. Insulation blocks 11 are arranged between the teeth of the wheel 10 and the teeth are engaged by a contact 12. The wheel 10 also carries a contact pin 13 to engage with a contact 14 on each revolution of the wheel 10. The contact pin 13

is eccentrically mounted on the wheel and moves in the path of a rotatable contact device 15 in the form of a star wheel having contacts 16, 17, 18, and 19. The rotatable contact element 15 is journaled on the base and is given a step by 5 step movement by the contact pin 13 during the rotation of the wheel 10. Mounted on the base are electric lamps 20 and 21, the lamp 20 being of one color and preferably green while the electric lamp 20 is of another color and preferably 10 red so that they can be easily distinguished from one another at a distance. The electric lamps 20 and 21 provide signals and if desired the lamps may be substituted for by other forms or types of signals. The electric lamp 20 is connected to the 15 contacts 16 to 19 by a conductor 22 and the electric lamp is also connected to the conductor 7 by a conductor 23. The wheel 10 is connected to the conductor 6 by a conductor 24 and a wiping element 25 that rides against the wheel 10 20 during the rotation thereof. The contact 14 is connected to one pole of a double control switch 26 by a conductor 27 and the contact 12 is connected to the other pole of the switch 26 by a conductor 28. The switch 26 is connected to the 25 electric lamp 21 by a conductor 29 and is also connected to the conductor 7 by a conductor 30 having a switch 31 preferably in the form of a push button. The conductor 30 between the electric lamp 21 and switch 31 has connected thereto a 30 conductor 32 which is in turn connected to a switch 33 and the latter is connected to the conductor 7 by a conductor 34.

The switches heretofore referred to are mounted on the base 1, as shown in Figure 1, in convenient reach of the timekeeper.

The green electric lamp 20 is for the purpose of indicating fighting periods and rest periods in a boxing match or prize fight while the red electric lamp is for the purpose of indicating seconds 40 and also a ten second signal preceding the fighting period within the rest period. The rotatable contact element 15 in the form of a star wheel in cooperation with the contact pin 13 controls the circuit to the electric lamp 20 in such 45 a way as to indicate a signal of the beginning of a round or fighting period of three minutes and to indicate the end of the fighting period and then indicate the rest period of one minute between said fighting period and the following 50 fighting period of three minutes. The ten second signal preceding the fighting period is given by the red electric lamp 21 by the timekeeper positioning the switch 26 to close the circuit through the conductor 27, contact 14 and contact pin 13. 55

It is to be understood that the timekeeper thus positions the switch 26 within the rest period so that ten seconds will elapse between the lighting of the electric lamp 21 and the lighting of the electric lamp 20 through the rotatable contact element 15. During the fighting period the timekeeper throws the switch 26 to include the contact 12 in circuit with the electric lamp 21 and should a fighter be knocked down or out during the fighting period, the instant the fighter falls the timekeeper actuates the push button 31 and the electric lamp 21 is then illuminated each second so that ten seconds can be easily counted in determining that the fighter is officially out and the fight ended thereby. It is to be understood that when the switch 26 is positioned to complete the circuit to the conductor 27 the switch 33 is closed and that during the entire operation of the device the main switch 8 is closed.

The clock 2 besides providing a power medium for the actuation of the signal control mechanism 9 also provides for the timekeeper a stop clock mechanism in that its operation can be controlled through the actuation of the main switch 8.

Having described the invention, I claim:

In a timing device an electrically actuated clock and a switch controlled electric circuit for the clock, a toothed metal wheel having insulator strips between the teeth thereof and means between the clock and wheel for turning the wheel, a metal pin projecting from the wheel, a star gear of insulating material to be turned when contacted by the pin, contacts between certain of the opposed teeth of the star gear to be engaged by the pin, a lamp, a conductor between the lamp, the contacts and one of the conductor wires of the circuit, a wiper contact engaging the toothed wheel and wired to the second conductor of the circuit, a spring contact in the path of contact with the pin, a conductor wire leading therefrom, a brush switch in wiping engagement with the periphery of the wheel, a conductor therefor, a switch swingable to engage with the terminal ends of each of said last named conductors, a conductor wire leading from said switch, a lamp connected to the said wire, and connections from the lamp to one of the conductor wires and including manual switches therein.

LEE A. DU ROCHER. 25
